sylvania

Application November 29, 1944, Serial No. 565,721

9 Claims. (Cl. 314—75)

1

This invention relates to regulator systems and, particularly, to regulators for governing the operation of movable electrodes of electric arc furnaces.

In operating an electric furnace of the movable electrode type it is desirable to automatically raise and lower each electrode in accordance with some furnace condition and to maintain a substantially constant electrode arc. Recently it has been found that there is a definite relation between the voltages and currents used in the arc circuit and that the arc current is usually too high for the voltage used. Instead of such high values of current for the low values of voltage usually used it is preferred to utilize a low tension voltage at a suitable value of low tension current to obtain the maximum kilowatt input with the best power factor. It is difficult, however, to get the furnace operators to use low tension low currents with the low tension voltages with the result that the arc furnaces will frequently and usually operate at a lower power factor than that which gives an efficient application of power.

An object of this invention is to provide a regulating system for arc furnaces in which provision is made to compensate the regulating system for changes in the power factor of the arc to limit the power factor at which the furnace is operated.

Another object of this invention is the provision in a furnace regulator system for controlling the position of an electrode of the furnace, of means responsive to the power factor of the arc for compensating the system whereby the regulator system positions the electrode in response to a function of both the magnitude and phase angle of the current flowing through the arc.

Other objects of this invention will become apparent from the following description when taken in conjunction with the accompanying drawing, in which:

Figure 1 is a diagrammatic view of circuits and apparatus illustrating an embodiment of this invention; and

Fig. 2 is a graph, the curves of which illustrate certain operating conditions of an arc furnace.

Referring to the drawing, and in particular to Fig. 1, an arc furnace 10 is illustrated having a metal receptacle or shell 12 containing a bath of material 14 and having three movable electrodes 16, 18 and 20 positioned adjacent thereto. The electrodes 16, 18 and 20 are directly connected to conductors 22, 24 and 26, respectively, which are connected to a suitable source of power through a power transformer (not shown). Means such as a flexible cable 28 and a pulley 30 are provided, being associated with each of the electrodes for raising and lowering the electrode. Three rectangular areas 32, 34 and 36 are indi-

2

cated each representing the apparatus associated with one of the three phases for operating the phase electrodes 16, 18 and 20, respectively. Since the operating mechanism for each of the three phases is identical, only one of the operating mechanisms is illustrated in detail and shown enclosed in the rectangular area 36.

As illustrated the flexible cable 28 may be wound upon a winding drum 38 operated by a reversible electrode motor 40. The electrode motor 40 comprises a field winding 42 disposed to be energized from any suitable direct current source, such as the battery 44, and an armature winding 46 connected by conductors 48 and 50 to be supplied with energy from a main generator 52 that is driven by an alternating current motor 54 and excited by an exciter generator 56.

The main generator 52 comprises an armature winding 58 connected to the conductors 48 and 50 and a field winding 60 disposed to be supplied with energy from the armature winding 62 of the exciter generator 56. As illustrated, one terminal of the armature winding 62 is connected through a self-exciting field winding 64 for the generator 56 and conductor 66 to a terminal of the field winding 60, the other terminal of the armature winding 62 being connected by conductor 68 to the other terminal of the field winding 60 of the main generator 52. The exciter generator 56 is also provided with two control field windings 70 and 72 which are disposed to be so energized as to oppose each other and to cooperate in controlling the excitation of the exciter generator 56.

The control field winding 70 is connected across the output terminals of a rectifier 74, the input terminals of which are connected to a current transformer 76 which is inductively associated with phase conductor 26 whereby the field winding 70 is supplied with a unidirectional current that is a measure of the alternating current flowing through the phase conductor 26 and the arc of that phase in the furnace 10. As illustrated, one terminal of the control field winding 70 is connected by a conductor 78 to an output terminal of the rectifier 74, the other terminal of the field winding 70 being normally connected through conductors 80 and 82, bridging contact member 84 of a current relay 86 and conductor 88 to the other output terminal of the rectifier 74. The conductor 82, bridging contact member 84 and conductor 88 are provided for normally shunting a resistor 90, the purpose of which will be explained more fully hereinafter.

The control field winding 72 is connected by conductors 92 and 94 to the output terminals of a full-wave rectifier 96, one of the input terminals of which is connected by conductor 100 to the casing or shell 12 of the furnace 10, the other input terminal being connected through an adjustable resistor 102 to the electrode 20. The

resistor 102 is provided for adjusting the voltage supplied to the rectifier 96 with respect to the voltage across the furnace arc. The control field winding 72 is thus energized at a voltage that is a measure of the drop in voltage across the furnace arc.

The resistor 90 referred to hereinbefore as being normally shunted from circuit with the field winding 70 is disposed under predetermined conditions to be connected in the circuit with the field winding 70 to impress a voltage thereon depending upon the power factor of the arc to increase the energization of the field winding 70 over the energization that is a pure measure of the current flowing through the electrode 20.

As illustrated, the resistor 90 is connected across the output terminals of a full-wave rectifier 104, the input terminals of which are connected across a resistor 106, the voltage drop across which is rectified and impressed across the resistor 90. The resistor 106 is disposed to be so connected in circuit with resistors 108 and 110 that the vector difference of the voltages across parallel connected resistors 108 and 110 is impressed on the resistor 106.

In order to provide that the vector difference of the voltages across resistors 108 and 110 is an indication of the power factor of the arc, the resistor 110 is disposed to be connected through a phase shifting circuit 112 to the secondary winding 114 of a transformer 116, the primary winding 118 of which is connected across phase conductors 24 and 26. The secondary winding 114 of the transformer 116 is connected across the series connected capacitor 120 and adjustable resistor 122, the resistor 110 being connected across the midpoint terminal of the secondary winding 114 and the junction of the series connected capacitor 120 and resistor 122. By adjusting the number of sections of the resistor 122 connected in the phase shifting network system 112, an adjustment is made in the voltage impressed across resistor 110.

The voltage impressed across resistor 108 is in opposition to that impressed across resistor 110 and is dependent upon the phase angle of the current flowing through the electrode 20. Thus resistor 108 is connected across the secondary winding 124 of a saturating transformer 126, the primary winding 128 of which is connected across the current transformer 130 which is inductively associated with the phase conductor 26. As illustrated, the energizing winding 132 of the current relay 86 is connected between the transformers 126 and 130 whereby the relay 86 is energized and responds to the current flowing through the conductor 26.

Thus the voltage across resistor 110 is constant depending upon the adjustment of the resistor 122 and the voltage across resistor 108 varies in magnitude and phase angle with variations of the phase angle between the current and voltage in the supply circuit. It is apparent that the vector difference applied to resistor 106 when rectified gives a direct current potential proportional to the phase angle difference between the arc voltage and current. When resistor 90 is connected in circuit with the control field winding 70, this direct current potential is in series with the normal polarity of the field winding 70 so that as the electromotive force due to an increase in lagging phase angle increases the net voltage applied to the control field winding 70 will increase.

In practice the relay 86 is designed so that

when a predetermined current flows through conductor 26 the relay is energized to actuate the bridging contact member 84 to a circuit opening position to connect the resistor 90 in circuit with the control field winding 70.

Referring to Fig. 2 of the drawing there is illustrated the relation between the current and power factor and kilowatts input to the furnace. As illustrated by curve 133 as the current flowing through the arc or electrode increases, the power factor decreases and as illustrated by curve 134, as the current increases the kilowatt input first increases and then drops off. The peak of efficient use of power is at about 80% power factor as represented by the vertical line 136 and it is preferred to limit the power factor of the arc to approximately this value. By design, the relay 86 is constructed so that its bridging contact member 84 is actuated to a circuit opening position at approximately the value of current flowing through the arc when the peak of the curve of the kilowatt input is reached or immediately thereafter. Thus the relay 86 is responsive to a predetermined flow of current through the arc for modifying and in this case increasing the energization of the control field winding 70 in response to changes in the power factor of the arc.

When the operation of the furnace is started, the phase shifting circuit 112 is adjusted to provide a predetermined constant voltage across resistor 110 in accordance with the power factor which it is desired to limit. When the operation is first started the three electrodes 16, 18 and 20 are in a raised position out of contact with the body of the material 14 which is to be heated in the furnace receptacle 12. Under these conditions no current will be flowing through the electrodes 16, 18 and 20 and no current will be flowing through the control field winding 70, the energization of which is a measure of the current through the phase circuit conductor 26. The voltage between the electrode 20 and the shell 12 will, however, be a maximum whereby the control field winding 72 will be fully energized.

The control field winding 72 thus excites the exciter generator 56 to develop a voltage which is applied to the main generator field winding 60 having a polarity to cause the generator 52 to build up in a direction to operate the motor 40 to move the electrode 20 downwardly. As the exciter voltage in the armature 62 builds up, the flow of current through the self-energizing winding 64 increases to increase the rate of voltage build up of the exciter generator 56 thus causing this voltage to build up more rapidly than it otherwise would. Thus under the influence of the field windings 64 and 72 the motor 40 is operated to rapidly lower the electrode 20 to a position where it contacts the material 14.

When the three electrodes 16, 18 and 20 are being lowered and the first one engages the bath 14, the voltage of the arc impressed across the rectifier 96 and consequently across the control field winding 72 collapses or drops to a very low value. Thus in effect, the control field winding 72 is shorted out of service and if the voltage on the control field winding 72 collapses it causes a corresponding reduction in the output voltage of the exciter generator 56 and of the main generator 52, which is applied to the electrode motor 48. When one of the other electrodes 16 or 18 is lowered sufficiently to also engage the bath of material 14 a current starts to flow through the bath between the electrodes and a resistance drop in voltage between the electrodes and the

casing 12 appears thus causing an increase in the voltage between the electrodes and the casing 12 and on the control field winding 72. The effect of the control field winding 72 on the exciter generator 56 is in a direction to tend to operate the motor 40 in a direction to lower the electrode 20 as explained hereinbefore. However, since current is now flowing through the conductor 26, a voltage is applied from the current transformer 76 through rectifier 74 to the control field winding 70 in a direction to oppose the flux developed by the field winding 72. The direction in which the motor 40 will now operate is therefore, dependent upon which of the two control field windings 70 and 72 predominate.

When the flux produced by the field winding 70 is greater than that produced by the control field winding 72, the flux will cause the exciter generator 56 to develop a voltage having a polarity such as to energize the main generator field winding 60 in a direction to impress a voltage on the motor armature 46 having a polarity to cause the motor 40 to operate in a direction to raise the electrode 20. In a similar manner if the flux developed by the control field winding 72 is greater than that developed by the control field winding 70, the polarity of voltage developed by the exciter generator 56 will be reversed thus impressing a voltage on the armature 46 of the motor 40 such as to cause the electrode 20 to be lowered. When the electrode is raised the arc is lengthened, the arc current decreases and the arc voltage increases and, when the electrode is lowered the arc current increases and the arc voltage decreases. The resulting effect is to move the electrode 20 to such a position that the flux developed by the two control field windings 70 and 72 neutralize each other in which position the electrode motor 40 will be at rest.

During the normal operation of the system of this invention the electrode 20 is maintained in a substantially constant position relative to the bath of material 14 so that the energization of the field windings 70 and 72 are substantially equal and in position to neutralize each other. This result may be obtained by adjusting the resistors in the input circuits for the rectifiers 74 and 96. If, however, the bath of material 14 should cave in on the electrode 20 thereby causing a short circuit, with the result that a large current flows through the electrode 20, and as soon as the current reaches the predetermined value as represented by the vertical line 136 of Fig. 2, the winding 132 of relay 86 is so energized as to actuate its bridging contact member 84 to an open circuit position, whereby the resistor 99 is connected in circuit with the control field winding 70.

As the flow of current through the electrode 20 and conductor 26 increases the vector difference of the voltages on resistors 108 and 110 increases whereby an increasing voltage is impressed across resistor 99. Since this voltage is of the same polarity as that of the control field winding 70 it is apparent that immediately upon the operation of the relay 86 the energization of the field winding 70 is so increased that the voltage output of the exciter generator 56 is increased to so energize the field winding 60 of the main generator 52 that the motor 40 is operated in a direction to effect an immediate upward movement of the electrode 20 whereby the current flowing through the conductor 26 is decreased to maintain it at a value approximating the value represented by the vertical line 136 of Fig. 2. As

soon as the electrode 20 is actuated to a position where the current is decreased to the predetermined value of power factor at which it is desired to limit the operation, the relay 86 is de-energized and the resistor 99 is shunted from the control field winding circuit whereby control of the operation of the regulator is again maintained by balance of energization of the field windings 70 and 72 in response to the current flow through and the voltage across the furnace arc. In practice, the relay 86 is so designed that once it is energized to the open circuit position, it remains in this position until the current is reduced to a value lower than the predetermined pick-up value, whereby continuous vibrating operation of the relay 86 is limited.

By utilizing the system of this invention, it is apparent that an automatic control of the positioning of the electrodes in an arc furnace is obtained so as to maintain a balance between the current and voltage of the arc. Further by this system it is possible to automatically limit the power factor of the arc and thereby operate the furnace so that the kilowatt input to the furnace is maintained at approximately its peak value to give maximum efficiency in the operation of the arc furnace.

Although this invention has been described with reference to a particular embodiment thereof, it is, of course, not to be limited thereto except insofar as is necessitated by the scope of the appended claims.

What is claimed is:

1. In a furnace-regulator system, the combination comprising, a movable electrode, a motor for operating the electrode, means for controlling the operation of the motor to control the arc, said means including a pair of oppositely disposed control voltages, one of said pair of control voltages being a measure of the voltage across the arc, the other one of said pair of control voltages being a measure of the current flowing through the arc, and relay means disposed for operation in response to only a predetermined flow of current through the arc to effect a modification of only said other one of said pair of control voltages in response to changes in the power factor of the arc.
2. In a furnace-regulator system, the combination comprising, a movable electrode, a motor for operating the electrode, means for controlling the operation of the motor to control the arc, said means including a pair of oppositely disposed control voltages, one of said pair of control voltages being a measure of the voltage across the arc, the other one of said pair of control voltages being a measure of the current flowing through the arc, and means responsive only to a predetermined flow of current through the arc for modifying only the other one of said pair of control voltages in response to changes in the power factor of the arc.
3. In a furnace-regulator system, the combination with a movable electrode, a motor for operating the electrode, and a main generator for supplying energy to the motor, of means for governing the operation of the motor to regulate the arc, said means comprising an exciter generator connected for exciting the main generator, a pair of oppositely energized control field windings for the exciter generator, means for energizing one of said pair of control field windings with a current that is a measure of the voltage across the arc, means for energizing the other one of said pair of control field windings with a current that is a measure of the current flowing through the

arc, and relay means disposed for operation in response to only a predetermined flow of current through the arc to effect a modification of the energization of only said other one of said pair of control field windings in response to changes in the power factor of the arc.

4. In a furnace-regulator system, the combination with a movable electrode, a motor for operating the electrode, and a main generator for supplying energy to the motor, of means for governing the operation of the motor to regulate the arc, said means comprising an exciter generator connected for exciting the main generator, a pair of oppositely energized control field windings for the exciter generator, means for energizing one of said pair of control field windings with a current that is a measure of the voltage across the arc, means for energizing the other one of said pair of control field windings with a current that is a measure of the current flowing through the arc, and means operative in response to only a predetermined value of current flowing through the arc for modifying only the energization of the other one of said pair of control field windings in response to changes in the power factor of the arc.

5. In a furnace-regulator system, the combination comprising, a movable electrode, a motor for operating the electrode, means for controlling the operation of the motor to control the arc, said means including a pair of oppositely disposed control voltages, one of said pair of control voltages being a measure of the voltage across the arc, the other one of said pair of control voltages being a measure of the current flowing through the arc, another source of control voltage responsive to the power factor of the arc disposed to be connected in circuit with the other one of said pair of control voltages, relay contact members for closing a circuit in shunt relation to said another source, and means responsive to a predetermined current flow through the arc for operating the relay contact members to remove the shunt and connect said another source of control voltage in circuit for modifying the other one of said pair of control voltages in response to changes in the power factor of the arc.

6. In a furnace-regulator system, the combination with a movable electrode, a motor for operating the electrode, and a main generator for supplying energy to the motor, of means for governing the operation of the motor to regulate the arc, said means comprising an exciter generator connected for exciting the main generator, a pair of oppositely energized control field windings for the exciter generator, means for energizing one of said pair of control field windings with a current that is a measure of the voltage across the arc, means for energizing the other one of said pair of control field windings with a current that is a measure of the current flowing through the arc, a source of control voltage responsive to the power factor of the arc disposed to be connected in circuit with the other one of said pair of control field windings, relay contact members for closing a circuit in shunt relation to the source of control voltage, and means responsive to a predetermined current flow through the arc for operating the relay contact members to remove the shunt and connect the source of control voltage in circuit with the other one of said pair of control field windings to modify the energization thereof in response to changes in the power factor of the arc.

5

7. In a furnace-regulator system, the combination comprising, a movable electrode, a motor for operating the electrode, means for controlling the operation of the motor to control the arc, said means including a pair of oppositely disposed control voltages, one of said pair of control voltages being a measure of the voltage across the arc, the other one of said pair of control voltages being a measure of the current flowing through the arc, a resistor in series circuit with the other one of said pair of control voltages, relay contact members for closing a circuit in shunt relation to the resistor, means for impressing a control voltage responsive to the power factor of the arc across the resistor, and means responsive to a predetermined current flow through the arc for operating the relay contact members to remove the shunt and connect the resistor in circuit with the other one of said pair of control voltages to effect a change therein in response to the power factor of the arc.

7. In a furnace-regulator system, the combination comprising, a movable electrode, a motor for operating the electrode, and a main generator for supplying energy to the motor, of means for governing the operation of the motor to regulate the arc, said means comprising an exciter generator connected for exciting the main generator, a pair of oppositely energized control field windings for the exciter generator, means for energizing one of said pair of control field windings with a current that is a measure of the voltage across the arc, means for energizing the other one of said pair of control field windings with a current that is a measure of the current flowing through the arc, and means operative in response to only a predetermined value of current flowing through the arc for modifying only the energization of the other one of said pair of control field windings in response to changes in the power factor of the arc.

8. In a furnace-regulator system, the combination with a movable electrode, a motor for operating the electrode, and a main generator for supplying energy to the motor, of means for governing the operation of the motor to regulate the arc, said means comprising an exciter generator connected for exciting the main generator, a pair of oppositely energized control field windings for the exciter generator, means for energizing one of said pair of control field windings with a current that is a measure of the voltage across the arc, means for energizing the other one of said pair of control field windings with a current that is a measure of the current flowing through the arc, another source of control voltage responsive to the power factor of the arc disposed to be connected in circuit with the other one of said pair of control voltages, relay contact members for closing a circuit in shunt relation to said another source, and means responsive to a predetermined current flow through the arc for operating the relay contact members to remove the shunt and connect said another source of control voltage in circuit for modifying the other one of said pair of control voltages in response to changes in the power factor of the arc.

9. In an electric arc furnace control having a charge portion in which the material to be melted is placed and a power circuit including a relatively movable electrode and a phase conductor therefor, in combination, a control means disposed to be normally energized in response to the flow of current in the phase conductor, means responsive to only a predetermined flow of current in the phase conductor for modifying the energization of said control means in response to changes in the power factor of the power circuit from a predetermined value, and means responsive to said control means when the energization thereof is so modified for moving the electrode so as to change the power factor of the power circuit in a direction toward the predetermined value.
